Development Company, a corporation of Del-
aware

No Drawing. Application December 31, 1938,
Serial No. 248,875

12 Claims. (Cl. 196—13)

This invention relates to the selective solvent extraction of hydrocarbon oils, and is more particularly concerned with the extraction of aromatic and/or olefinic hydrocarbons from lighter hydrocarbon oils.

Light hydrocarbon oils such as naphthas generally contain a mixture of paraffinic, olefinic and aromatic hydrocarbons. The relative proportions of each depend very largely upon the crude from which the naphtha is obtained and method of production. It has been found that the aromatic fractions of naphthas are characterized by high octane number which makes them especially suitable for anti-detonation motor fuels either alone or in blends with other fuels of lower octane number. The aromatic fractions are also especially useful as solvents for lacquer, paints, varnishes, enamels and coating compositions generally. The olefines are chemically reactive and it is often desired to separate these from paraffin fractions.

Various methods have been proposed for separating the paraffinic from the olefinic or aromatic hydrocarbons in order to obtain a highly olefinic or aromatic fraction. The simplest of these methods is solvent extraction in which the naphtha is treated with a solvent which has a preferential solvent power for aromatics or olefins and relatively little or no solvent power for paraffinic hydrocarbons. Naturally, the best solvents for this purpose are those which have the following properties: (1) high solubility for aromatics or olefins at temperatures at which the paraffinics are substantially insoluble, (2) relatively high miscibility temperatures with the naphtha to avoid the necessity of chilling to cause separation of phases, (3) a boiling point widely different from that of naphtha so that the solvent may be easily recovered from the treated oil, and (4) stability and high decomposition temperature to avoid loss of solvent.

The present invention is concerned with new solvents for extracting aromatic or olefinic hydrocarbons from naphthas. The nature of these solvents and the manner of using them will be fully understood from the following description:

It has been found that monophenolic ethers of ethylene glycol and polyethylene glycols and their derivatives, such as the monophenyl or monotolyl ethers of such glycols, have high selective solvent power for olefinic and aromatic hydrocarbons, and are suitable for extracting them from mixtures with paraffinic hydrocarbons. The solvents of this type may be described

generally by means of the following structural formula:

where "n" is at least 2, and the ring should be taken as representative of any aromatic ring: also where "R" can be either hydrogen atom or alkyl radical. Monophenyl and monotolyl ethers of ethylene glycol, di-ethylene glycol, tri-ethylene glycol, tetraethylene glycol and pentaethylene glycol are suitable. Specific examples are mono-phenyl ether of ethylene glycol (which is frequently named beta-phenoxy ethyl alcohol) and beta-phenoxy propyl alcohol. These solvents may also be used in admixture with di-ethylene glycol, tri-ethylene glycol, tetraethylene glycol and also dioxy derivatives of the glycol series $C_nH_{2n+2}O_2$, such as ethylene, propylene and butylene glycols, tri-, tetra- and pentamethylene glycols, etc.

Beta phenoxy ethyl alcohol is the monophenyl ether of ethylene glycol and has the following properties:

Specific gravity at 60° F.	1.112
Boiling point at 760 mm. Hg	458° F.
Refractive index at 20° C.	1.5390
Percent soluble in water at 70° F.	2% by volume
Percent water soluble in beta phenoxy ethyl alcohol	10% by volume

Benzene, toluene and xylene are completely miscible in all proportions with beta phenoxy ethyl alcohol at 70° F. A Mid-Continent naphtha having a boiling range between 192 and 288° F. and a gravity, "A. P. I.", of 61.3 is completely miscible with an equal volume of beta phenoxy ethyl alcohol only at 170° F.

In carrying out the extraction, the naphtha is first mixed with from 75 to 200% of beta phenoxy ethyl alcohol. The mixture is heated, if necessary, to a temperature between 50 and 100° F. and allowed to settle. The two layers formed are separated, and the aromatic hydrocarbons recovered from the bottom or extract layer by distillation or other suitable means.

The extraction may also be carried out in a continuous counter-current manner either in a single tall tower or in a series of stages.

Mixtures of the phenoxy alcohols with tri-ethylene glycol or other glycols mentioned above frequently exhibit greater selectivity than the phenoxy alcohol alone. Mixtures of approximately equal proportions of each solvent, for

example, are suitable, although other mixtures can be used.

It is also frequently advantageous to add from 5 to 8% of modifying agents such as water to the phenoxy alcohol, either when used alone or in admixture with triethylene glycol. The small amount of water still further increases the selectivity of the solvent for aromatics or olefins.

The following experiments illustrate the invention:

10 A synthetic blend of naphtha and aromatics is prepared by adding 15% by volume of equal proportions of benzene, toluene and xylene to a naphtha of the following characteristics:

15	Source	Mid-Continent crude
	Gravity, °API	61.3
	Refractive index at 20° C	1.4080
	Aniline point	132° F.
20	Initial boiling point	192° F.
	50% off at	220° F.
	Final boiling point	288° F.

25 The gravity and refractive index of the blend are as follows:

Gravity, °API	56.3
Refractive index at 20° C	1.4208

30 This synthetic blend is then extracted in a seven-stage counter-current treater with various amounts of beta phenoxy ethyl alcohol, either alone or in admixture with triethylene glycol and water. The counter-current treatment is 35 carried out at about 70° F. in the usual manner. Before obtaining final inspections on the raffinate phase, the raffinate is water-washed to a constant refractive index. The extract is recovered from the extract phase by steam distillation.

40 The overhead from the steam distillation is collected in iced receivers to prevent loss of light ends and is then waterwashed to a constant refractive index. The solvent is dehydrated by vacuum distillation and reused.

45

Example 1

50 The synthetic blend is treated at 70° F. with 75% of beta phenoxy ethyl alcohol. The yields and characteristics of the raffinate and extract are as follows:

55		Raffinate	Extract
	Gravity, °API	61.3	47.7
	Refractive index at 20° C	1.4061	1.4432
	Aniline point	133° F.	

60 Yield on charge percent 64.8 35.2

Example 2

65 The blend is treated at 80° F. with 100% of a mixture containing 92% beta phenoxy ethyl alcohol and 8% water. The results are as follows:

70		Raffinate	Extract
	Gravity, °API	60.1	45.0
	Refractive index at 20° C	1.4120	1.4507
	Aniline point	126° F.	

75 Yield on charge percent 76.3 23.7

Example 3

The blend is treated at 70° F. with 150% of a mixture of 50% beta phenoxy ethyl alcohol and 50% triethylene glycol. The results are as follows:

	Raffinate	Extract
Gravity, °API	60.1	41.7
Refractive index at 20° C	1.4120	1.4611
Aniline point	126° F.	

Example 4

The blend is treated at 70° F. with 150% of a mixture consisting of 50% beta phenoxy ethyl alcohol and 50% triethylene glycol. In this experiment water is added to the extract phase at the end of the treater in an amount of about 50% of the volume of extract present in the extract phase. The results are as follows:

	Raffinate	Extract
Gravity, °API	60.3	38.9
Refractive index at 20° C	1.4110	1.4690
Aniline point	126° F.	

Yield on charge percent 83.0 17.0

It will be observed that whereas the refractive index of the original blend is 1.4208, the refractive index of the raffinate obtained in each of the above examples is between 1.4081, as in Example 1, and 1.4120, as in Examples 2 and 4, indicating that the raffinate phase is approaching very closely the original naphtha content of the blend which has a refractive index of 1.4080. In Example 1, it should be noted that the refractive index of the raffinate is 1.4081, indicating that this raffinate is substantially the same as the original naphtha.

Example 5

To illustrate the use of other selected solvents, phenoxy propanol was employed. The feed stock extracted was a synthetically prepared mixture of aromatics with naphtha (boiling range 100°-320° F.) which had been carefully treated with sulfuric acid. The extraction temperature was 38° F. and 100 parts of the phenoxy propanol were used to 100 of the feed in a single batch extraction.

	Feed	Extract (dry)	Raffinate (dry)
Refractive index	1.4152	1.4174	1.4125
Percent aromatics	8.5	11.5	5.5
Yield on feed	percent 50	50	50

60 The yield and efficiency can be improved by counter-current methods of extraction.

Example 6

65 Using cresoxy ethanol at 37° F. in a similar synthetic blend of aromatics and paraffinic naphtha, with a single batch treat with 28.6% of solvent, the results were as follows:

	Feed	Extract (dry)	Raffinate (dry)
Refractive index	1.4152	1.4178	1.4146
Aromatics	percent 8.8	11.5	8.0

Example 7

To illustrate the removal of olefins from paraffins a synthetic mixture of amylene and hexane was made up and extracted with 85.2 parts of phenoxy propanol per 100 parts of feed at 50° F. in a single batch extraction. The feed contained 18.6% of olefins, and the extract which amounted to 37% by volume contained 21.2% olefins. Counter-current methods will improve these results.

Example 8

Using a 72.5% treat with cresoxy ethanol at 50° F. in a single batch extraction, a mixture containing 44.5% amylene and 55.5% hexane gave 36.2% by volume of an extract (dry) which contained 49% olefins.

Although the description and examples are concerned with the treatment of naphthas, it is to be understood that these solvents may likewise be used to treat higher boiling range fractions.

It will be understood that the solvent treating process in which these phenoxy alcohols are used is subject to a great many variations and combinations with other processes, and the present invention contemplates the use of these solvents under any conditions and in all the various modifications which have been proposed for solvent treating processes in connection with other selective solvents. By way of illustration, but not of limitation, such modifications include withdrawal of extract, addition of water or other modifying agent thereto and subsequent return of cycle oil to the treating step; the use of other solvents having preferential selective solvent power for paraffinic hydrocarbons in conjunction with the phenoxy alcohol; the maintenance of a temperature gradient in the treating tower or from stage to stage; the combination of a cracking or destructive hydrogenation process with the solvent treating process; the combination of the solvent treating process with a subsequent hydrogenation or hydrofining of the extract, etc.

The present application is a continuation in part of Serial No. 162,875, filed September 8, 1937.

This invention is not limited by any theories of the mechanism of the reactions nor by any details which have been given merely for purposes of illustration, but is limited only in and by the following claims in which it is our intention to claim all novelty inherent in the invention.

We claim:

1. The method of separating paraffinic hydrocarbons from mixtures containing the same with non-paraffinic fractions, which comprises extracting the mixture with a solvent comprising an aromatic ether of a glycol whereby the non-paraffinic fractions are concentrated in the solvent.

2. The method of separating paraffinic hydrocarbons from mixtures containing the same with non-paraffinic fractions, which comprises extracting the mixture with a solvent comprising a monophenolic ether of a glycol, whereby the non-paraffinic fractions are concentrated in the solvent.

3. The method of separating paraffinic hydrocarbons from mixtures containing the same with non-paraffinic fractions, which comprises extracting the mixture with a solvent comprising a monophenyl ether of a glycol, whereby the non-paraffinic fractions are concentrated in the solvent.

4. The method of separating paraffinic hydrocarbons from mixtures containing the same with non-paraffinic fractions, which comprises extracting the mixture with a solvent comprising beta phenoxy ethyl alcohol, whereby the non-paraffinic fractions are concentrated in the solvent.

5. The method of separating paraffinic hydrocarbons from mixtures containing the same with non-paraffinic fractions, which comprises extracting the mixture with a solvent comprising beta phenoxy ethyl alcohol and a polyethylene glycol, whereby the non-paraffinic fractions are concentrated in the solvent.

6. The method of separating paraffinic hydrocarbons from mixtures containing the same with non-paraffinic fractions, which comprises extracting the mixture with a solvent comprising beta phenoxy ethyl alcohol, triethylene glycol and 5 to 8% of water, whereby the non-paraffinic fractions are concentrated in the solvent.

7. The method of obtaining a highly aromatic fraction from a naphtha containing aromatic and paraffinic hydrocarbons which comprises extracting the naphtha with a solvent comprising a monophenolic ether of a glycol, separating the two phases thereby formed and recovering the aromatic hydrocarbons from the extract phase.

8. Process according to claim 7 in which the solvent comprises beta phenoxy ethyl alcohol.

9. Process according to claim 7 in which the solvent comprises beta phenoxy ethyl alcohol and triethylene glycol.

10. Process according to claim 7 in which the solvent comprises beta phenoxy ethyl alcohol, triethylene glycol and 5 to 8% of water.

11. The method of obtaining a highly olefinic fraction from a naphtha containing olefinic and paraffinic hydrocarbons which comprises extracting the naphtha with a solvent comprising a phenolic ether of a glycol, separating the two phases and recovering the olefinic hydrocarbons from the extract phase.

12. Method according to claim 11 in which the extraction is carried out with beta phenoxy ethyl alcohol.
